UNITED STATES PATENT OFFICE

JEAN DELATTRE SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

DEPHLEGMATOR

Application filed June 21, 1926. Serial No. 117,339.

This invention relates to improvements in dephlegmators. The object of the invention is to obtain an improved form of apparatus, which will insure a more close and accurate fractionation of liquids of different boiling points.

In the particular form of my invention, I have shown the apparatus as applied to a cracking process and apparatus, and will hereinafter describe its use, in order that its operation may more clearly appear. It is to be understood however, that as an apparatus, it is not limited to any particular use, and the invention is in no sense limited to the cracking of oil.

In the drawings, Fig. 1 is a more or less diagrammatic flow sheet showing the application of the invention to a cracking process.

Fig. 2 is a fragmentary sectional elevation 20 of the dephlegmating tower.

Fig. 3 is a sectional view taken on lines 3—3 of Fig. 2.

Fig. 4 is an enlarged sectional view of one of the cap members.

Referring to the drawings, 1 designates a furnace in which is mounted a cracking coil 2 having transfer line 3 leading to an expansion chamber 4, preferably located outside of the fire zone. The expansion chamber 4 is provided with a residuum drawoff 5 and at its upper end a vapor outlet 6 leading to the lower side of the dephlegmator 7. The construction of this dephlegmator which forms an important feature of this invention, will be hereinafter more described in detail. The vapors pass out of the top of the dephlegmator through the vapor outlet pipe 8 leading to the water condenser 9 and thence to the receiver 10. The receiver 10 may be provided with gas outlet 11 and liquid drawoff

12. The raw oil may be fed by the raw oil pump 13 from any suitable source of supply through the line 14 through the inlet side 15 of the cracking coil. If desired, part or all of the feed oil may be fed into or near the top of the dephlegmator through the pipe 16. The lower end of the dephlegmator is provided with the drawoff pipe 17 leading to the 50 inlet side of the heating coil and adapted to

cool both the reflux condensate and the raw charging stock.

In the line 17 is interposed a reflux pump 18, which may be by-passed if desired, as shown at 19. If desired, pressure distillate 55 may be fed into or near the top of the dephlegmator from the receiver 10 by means of the pipe 20 and pump 21. In the various pipes herein described, are interposed suitable throttle valves 22 through which the pressure may be controlled, or the by-pass lines herein referred to, used. The arrangement is such that if desired, a differential pressure may be obtained on various parts of the system and given quantities of the oil fed to given parts of the system, but inasmuch as these features do not form primarily the essence of this invention, it is not thought necessary to describe them in detail. However, in carrying out the process, fuel oil for example, may be fed through the heating coil and there subjected to a pressure of say 150 to 500 pounds, and thence to the expansion chamber where the same pressure or a reduced pressure may be employed.

The residuum may be drawn off from the bottom of the expansion chamber, and the vapors passed into the dephlegmator 7, which dephlegmator 7 may be under the same pressure as the heating coil, or the expansion chamber, or may be at a reduced pressure. The temperature of the dephlegmator may be so controlled that only the desired character of the distillate as for example, gasoline, will pass into the receiver, while the vapors of higher boiling point will condense in the dephlegmator, and be returned with the fresh charging stock to the cracking coil. While I have shown the reflux condensate as returning to the cracking coil, it may of course, be directed elsewhere.

Coming now more particularly to the structure shown in Figs. 2, 3 and 4, in the inside of the dephlegmator 7 is mounted a series of spaced apart superimposed plates 23, which plates 23 are each provided with a plurality of upstanding open ended channels or tubes 24 which extend across the area of the plate 23 as shown more clearly in Figs. 2 and 3. Mounted above each of the tubes 24 is an en-

larged cap member 25 which cap member 25 comprises a perforated plate 26 and a collar 27, which collar consists of a circular or upper flange 28 extending above the perforated member 26, and a lower flange 29 extending 5 down below and surrounding the upper end of the corresponding tube 24. The caps 25 are or may be supported above each tube 24 by a suitable supporting spider 30. This 10 spider consists of say, three short arms extending upwardly around the upper end of each tube 24, sufficient to support the caps without in any way obstructing the vapors. Depending from each plate 23 are a series of 15 downwardly extending open ended tubes 31, the upper ends of which tubes project slightly above the plate as shown at 32, and provided with the spaced cap members 33 suitably supported thereabove. The lower end of 20 each tube 31 terminates just short of the perforated plate of the corresponding cap member.

In carrying out the invention, as shown 25 the vapors first pass through the tubes 24 of the lowermost plate and thence outwardly and downwardly under the flanges 29 as shown at *a*. The vapors which are not condensed, then pass up through the tubes 24 of the next superimposed plate. They 30 continue thus until they reach the top of the dephlegmator when those that are still vapor, pass out through the pipe 8. The reflux condensate or the remainder of reflux condensate and raw charging stock (including pressure 35 distillate if such is fed overhead) pass downwardly as follows: At the uppermost plate the liquid will first accumulate in a small shallow pool as shown at *b*, and thence overflow by the cap members 33 through the pipes 31 40 down onto the corresponding perforated plate 26. Through the perforations in the plate 26, the liquid will fall in a stream down onto the plate 23 just below and thence overflow through the pipes 31 as before, and so on down 45 until the liquid reaches the bottom of the dephlegmator when it will be drawn out through the reflux pipe 17.

The arrangement is such that the vapors do not at any time bubble up through the 50 pools of liquid, but on the contrary, the construction is such that the shallow liquid pool maintained in each plate 23 is sufficient to create a liquid seal on the pipes 31, thus preventing the vapors from passing up through 55 said pipes 31. However, the liquid pools are not deep enough to reach the lower end of the flanges 29 of the cap members 25, and accordingly the vapors will pass out through the open space between the lower end of said cap 60 members and corresponding pool. Furthermore, the perforations on the plate 26 are of such dimensions as to maintain over said plate a depth of liquid sufficient to prevent the liquids from passing upward through said 65 perforations. The surface of the pool *c*

maintained over each plate 26 is above the bottom end of the pipe 31 leading to said pool so as to prevent vapors from passing up through the pipe 31.

By means of the present invention, I obtain 70 a more close and accurate fractionation and separation of the various constituents of the vapors, and the arrangement of the dephlegmator may be such that only end point gasoline passes into the receiver. It will be noted 75 that in the present invention the vapors are passed first upwardly through the pipes 24 and thence downwardly under the caps 25. The liquid passes downwardly and insures a maximum contact between the descending 80 streams and the vapors ascending through the dephlegmator.

I claim as my invention:

1. A dephlegmator consisting of a casing, 85 a plurality of spaced foraminated plates mounted therein, open ended vapor pipes extending from one side of each plate, and open ended liquid pipes extending from the opposite side of each plate, the vapor pipes of one plate being in substantial alignment with 90 the liquid pipes of the next highest plate, and means for preventing the vapors passing through the liquid pipes.

2. In a dephlegmator, the combination 95 with a casing, of a plurality of spaced plates mounted therein, each of said plates having a plurality of open ended upwardly projecting pipes, a cap member mounted above each of said pipes, said cap member having a flange projecting below and surrounding the upper end of each of said pipes, and means for making a substantial liquid seal on the upper portion of each cap.

3. In a dephlegmator, the combination 100 with a casing, of a plurality of spaced plates mounted therein, each of said plates having open ended upwardly projecting pipes, a spaced cap member for each pipe having a depending flange surrounding the upper end thereof, each of said cap members having a 105 perforated top portion.

4. In a dephlegmator, the combination 110 with a casing, of a plurality of spaced plates mounted therein, each of said plates having a plurality of open upwardly projecting pipes 115 through which vapors ascend, means for subjecting said vapors to a descending spray of liquid, and means for guiding said vapors in their travel through said liquid spray in a path upward over the upper rim of said pipe then outward and downward below the upper rim on the outside of the pipe.

5. In a dephlegmator, the combination 120 with a casing, of a plurality of spaced plates mounted therein dividing said casing into a plurality of chambers, each of said plates having a plurality of open upwardly projecting pipes through which vapors ascend to the common chamber thereabove, means 125 for subjecting said vapors from each pipe to

an individual downwardly directed spray of liquid, and means for passing said vapors from each chamber to the one thereabove without bubbling through the liquid collecting on said plates.

6. In a dephlegmator, means for dividing the vapors to be treated into a plurality of individual upwardly directed streams, means for subjecting each of said streams to an individual downwardly directed spray of liquid, and means for reversing the direction of flow of said streams while within the confines of said sprays.

7. In a dephlegmator, the combination with a casing, of a plurality of spaced liquid receiving plates mounted therein dividing said casing into a plurality of chambers, means for guiding vapors from one of said chambers to the chamber thereabove in a plurality of individual streams without bubbling through the liquid on said plates, and means in the second chamber spaced below the upper plate thereof for directing an individual spray of liquid against a plurality of said vapor streams.

JEAN DELATTRE SEGUY.
